UNITED STATES PATENT OFFICE

117,155

DESIGN FOR A PHOTOGRAPHIC CAMERA OR SIMILAR ARTICLE

Oscar Steiner, Irondequoit, and Charles H. Roth,
Jr., Rochester, N. Y., assignors to The Folmer
Graflex Corporation, Rochester, N. Y., a cor-
poration of Delaware

Application December 31, 1938, Serial No. 82,111

Term of patent 14 years

To all whom it may concern:

Be it known that we, Oscar Steiner and Charles H. Roth, Jr., citizens of the United States, and residents respectively of Irondequoit and Rochester, county of Monroe, and State of New York, have invented a new, original, and ornamental Design for a Photographic Camera or Similar Article, of which the following is a specification, reference being had to the accompanying drawings, forming part thereof.

Fig. 1 is a front elevation of the photographic camera or similar article with the door open and the wire view finder elevated;

Fig. 2 is a right side elevation with the camera

bed down, the bellows partly extended and the wire finder folded down;

Fig. 3 is an isometric view showing the photographic camera or similar article closed; and

Fig. 4 is a rear perspective view of the photographic camera or similar article shown in Fig. 1, but with the view finder parts folded down.

We claim:

The ornamental design for a photographic camera or similar article, substantially as shown and described.

OSCAR STEINER.
CHARLES H. ROTH, JR.
